Attorney

UNITED STATES PATENT OFFICE

IRVING A. GREEN, OF WORCESTER, MASSACHUSETTS, ASSIGNOR TO THE WASHBURN COMPANY, OF WORCESTER, MASSACHUSETTS, A CORPORATION OF MASSACHUSETTS

REINFORCED WIRE FABRIC AND METHOD OF MAKING THE SAME

Application filed March 15, 1930. Serial No. 436,204.

The present invention relates to a reenforced wire fabric and method of making the same, the invention having for its object to provide a wire fabric that will be stronger and more durable than wire fabrics heretofore made.

The invention has particular utility in the manufacture of ordinary wire screening in which the warp and weft wires are uniformly spaced, the invention contemplating the employment of a novel arrangement of warp wires whereby the resulting screening possesses greater strength and durability than wire screening heretofore made, in the usual manner. Screening produced by the practice of my invention is particularly adapted for use in the manufacture of kitchen utensils, such as strainers and the like, which are subjected to such hard usage as to bend and deform wire screening of the usual type. The above and other advantageous features of my invention will hereinafter more fully appear with reference to the accompanying drawing in which—

Fig. 1 represents the arrangement of the warp wires preparatory to weaving the reinforced fabric of my invention.

Fig. 2 shows a portion of the completely woven fabric.

Fig. 3 is a sectional view along the line 3—3 of Fig. 2, looking in the direction of the arrows.

Fig. 4 is a sectional view along the line 4—4 of Fig. 2, looking in the direction of the arrows.

Fig. 5 shows a portion of the reenforced wire fabric employed in a utensil.

Like reference characters refer to like parts in the different figures.

In making a fabric in accordance with my invention, two sets of warp wires 1a and 1b are arranged in the healds of the loom, equally spaced from each other in accordance with the mesh of the screening which it is desired to produce. In addition to the equally spaced warp wires, there are also provided groups of reenforcing warp wires 2a and 2b which are disposed at intervals across the warp in accordance with the degree of reenforcing desired. As shown, the several groups of

reenforcing wires 2a are threaded through the same heald as the regular warp wires 1a while the reenforcing wires 2b are threaded through the same heald as the wires 1b. In weaving the fabric, the weft wires 3 are introduced in the usual manner through the shed each time it is opened, so that the resulting fabric shown in Fig. 2 presents a mesh with openings of uniform size throughout, except along the groups of reenforcing warp wires 2a, 2b where the fabric is continuous.

In the weaving, each group of reenforcing warp wires 2a or 2b is handled as a unit, that is to say, all the wires 2a are moved in unison by the heald shafts, while the wires 2b are moved in the opposite direction in opening the shed. Thus the parallel wires 2a of one group are oppositely bent with respect to the parallel wires 2b of the adjacent groups, as will also be clearly evident from Fig. 3, this arrangement being carried on throughout the fabric.

As a result of the presence of the groups of parallel reenforcing warp wires 2a and 2b in the completed fabric of Fig. 2, wire fabric made in accordance with my invention possesses much greater strength and durability as compared to wire fabric heretofore constructed with uniform spacing between the weft and warp wires. The strengthening effect, resulting from the presence of the reenforcing warp wires, is particularly noticeable when the fabric is bent into rounded form, as in a utensil of the strainer type, for then, as indicated in Fig. 5, the reenforcing wires extending across the rounded body of the strainer give considerable rigidity to the bowl, particularly when the reenforcing wires are secured around the rim of the strainer. Obviously reenforced fabric made in accordance with my invention possesses many other uses, as for example in window screens to be used in places where they are liable to be struck by hard objects.

I claim,

1. A wire fabric comprising a plurality of equally spaced warp and weft wires woven to provide a uniform mesh, and groups of closely lying parallel warp wires disposed at intervals between the spaced warp wires, each

group comprising a multiplicity of wires of substantially the same diameter as the weft wires, with all the wires of each group passing alternately over and under successive weft wires, and all of said wires passing as a unit on one side of each weft wire.

2. An improved method of making wire fabric which consists in providing equally spaced warp wires with groups of closely lying warp wires disposed at intervals between the warp wires, and then inserting weft wires between the warp wires at equal intervals, the wires of each warp group being uniformly interwoven with the weft wires and being treated as a single warp wire during weaving.
